UNITED STATES PATENT OFFICE.

ARGYLE CAMPBELL, OF CHICAGO, ILLINOIS, ASSIGNEE TO ENTERPRISE RAILWAY EQUIPMENT COMPANY, OF CHICAGO, ILLINOIS, A CORPORATION OF ILLINOIS.

DOOR-OPERATING MECHANISM.

Application filed December 10, 1921. Serial No. 521,291.

To all whom it may concern:

Be it known that I, ARGYLE CAMPBELL, a citizen of the United States, residing at Chicago, in the county of Cook and State 5 of Illinois, have invented a certain new and useful Improvement in Door-Operating Mechanisms, of which the following is a full, clear, concise, and exact description, reference being had to the accompanying drawings, forming a part of this specification.

This invention relates to improvements in door operating mechanisms.

One object of the invention is to provide a simple, efficient and easily operable mechanism for closing doors and maintaining the same in closed position.

More specifically, the object of the invention is to provide a door operating mechanism especially adapted for general service 20 or gondola type of dump cars and in which the operating mechanism for the doors automatically and readily adapts itself to varying conditions to always insure the easiest possible operation.

In the drawing forming a part of this specification, Figure 1 is a vertical, transverse, sectional view of a portion of a drop bottom gondola or general service car showing my improvements in connection therewith. In this figure the section includes only approximately half of the width of the car, it being understood that the car will be similarly constructed on the opposite side of the center sill. Figure 2 is a top plan view of 30 the construction illustrated in Figure 1. And Figure 3 is a vertical, longitudinal, sectional view corresponding to the section line 3-3 of Figure 1.

In said drawing, the car is shown as provided with an underframe comprising center sills 10, cross bearers or needle beams 11, side stakes 12, and side sheets 13, with an additional longitudinally extending floor strip 14 along the sides of the car. In gondola and general service types of cars, it is customary to provide a plurality of floor doors intermediate the trucks on opposite sides of the center sill. Only one such door is shown in the drawing as it is believed that 45 this is sufficient to fully illustrate the invention. Such a floor door is shown at 15, the same being pivotally attached along its inner edge to suitable hinge brackets 16 secured to the center sill of the car, the door 50 swinging about an axis parallel to the cen-

ter sill and with the free edge of the door adjacent the side of the car.

For operating all the doors on one side of the car, I preferably employ a single longitudinally extending shaft 17, the same being 60 supported in suitable bearing bracket castings 18 riveted to the cross bearers 11. Each of the bearing brackets 18 is provided with a horizontally extending bearing slot 19, the latter preferably having a shallow depression as indicated at 119 at their outer ends to allow the shaft to drop down slightly when in inoperative position corresponding to the open position of the doors.

Mounted on each door 15 are preferably 70 two slidably mounted latches or bars 20, one near each side edge, only one of such latches being shown in the drawing. Each latch 20 is horizontally freely slidably mounted inwardly and outwardly within a suitable 75 housing or guide casting 21 riveted to the under side of the door adjacent the free edge thereof. Each latch 20 comprises a main stem 22 of non-circular form and preferably 80 rectangular so as to prevent the same from turning or twisting when sliding back and forth horizontally within the guide casting 21. At its outer end, each latch 20 is formed with a relatively enlarged head 23 having a top horizontal bearing face 24 engaging the 85 under face of the sheet metal door, and presenting a shoulder 25 which in turn is adapted to engage with the outer end of the guide casting 21 to limit the inward movement of the latch with respect to the door. The 90 outer face of each head 23 is preferably provided with a series of teeth 26 which extend partly around the bottom of the head 23, as illustrated in Figure 1. Each latch 20 is limited in its outward movement with 95 respect to the door, by any suitable means such as the cross key 27 which is adapted to engage the inner end of the guide casting 21 upon extreme outward movement of the latch.

The shaft 17 has secured thereto at proper intervals therealong, winding drums 28 preferably having helical grooves 29 therein within which are adapted to wind flexible connections such as the chain 30, one end of which is secured to the drum as at 31 and the other end of which is pivotally connected to the corresponding head 23 by a U-shaped link 32 and pivot-forming rivet 33. The U-shaped link 32 is preferably laterally de- 100 105 110

flected as indicated in Figure 3 so as to clear the toothed wheel 34 rigidly secured to the shaft and which is adapted to cooperate with the toothed head 23.

5 In Figure 1, the position of the parts corresponds to the closed position of the doors and it will be noted that the latch 20 is in approximately its extreme outermost position and the shaft 17 is in its extreme innermost position within the bearing slot 19. To open the doors, the shaft 17 is rotated in a clockwise direction. Due to the fact that the shaft 17 is free to move outwardly within the bearing slots 19 and the latches 20 are free to move inwardly on the doors, the first action may be either the inward movement of the latches or the outward movement on the shaft, dependent upon which of the elements is under the greatest amount of 20 friction. The relative movements of the latches and shaft, the former inwardly and the other outwardly, continues until the point of load from the doors to the shaft passes beyond the free edge of the doors 25 whereupon the latches, if the same have not been pushed fully inwardly, will be forced the remainder of the distance inwardly and the shaft 17 pushed farther outwardly along the bearing slots 19, the doors then being 30 free to fall under the weight of the load thereon and the flexible connections unwinding from the shaft, as will be apparent. In the final opening movement of the doors, the shaft 17 will be forced to the outer end 35 of the bearing slots 19.

To close the doors, the reverse operation takes place, that is, a rotation of the shaft 17 in a counter-clockwise direction. During the first part of the closing operation 40 the flexible connections will be wound around the drums and, toward the end of the operation, the shaft 17 will be pulled inwardly of the bearing slots and the latches pulled outwardly within the guide castings 45 21. On account of the independent movements allowed the latches and the shaft, the parts will readily accommodate themselves to varying conditions and greatly facilitate the final engagement or interlocking of the 50 toothed or serrated wheels 34 and the toothed or serrated heads of the latches until the shaft is brought to the position shown in Figure 1.

I am aware that it has heretofore been 55 customary to employ an operating shaft bodily shiftable to a position under the floor door of a car and engageable directly with the door or a shoe or the like rigidly secured thereto. Much difficulty has been 60 encountered however in such mechanisms under service conditions due to variations which occur in the manufacture and assembling of the parts and in operation, particularly with respect to the effective length 65 of the flexible connection between the points

of attachment to the shaft and the point of attachment to the door or rigid part thereon and also due to torsion of the shaft. Under the conditions indicated, where there are a plurality of doors governed by the same 70 operating shaft, some doors or the rigid parts thereon will engage with the shaft prior to engagement of other doors with the shaft, with the result that the flexible connections at some points must stretch or be distorted or the shaft further distorted or, in the case of those doors last to engage properly with the shaft, said doors will not be properly supported. With my arrangement, variable conditions such as referred 75 to, will be automatically compensated for both during the closing operation and the opening operation of the doors by the automatic relative adjustment of the sliding latches and the shaft, permitting them to always properly register, thereby reducing 80 and minimizing the strains imposed upon the parts and reducing the amount of power necessary to open and close the doors.

As will be understood by those skilled in 85 the art, any suitable mechanism may be employed for rotating the shaft 17, such as the pawl and ratchet devices now well known in the art.

I have herein shown and described what 90 I now consider the preferred manner of carrying out the invention, but the same is merely illustrative and I contemplate all changes and modifications that come within the scope of the claims appended hereto. 100

I claim:

1. In a door operating mechanism for a vehicle having a pivoted door and a frame, the combination with a rotatable and bodily movable shaft supported from the frame 105 adjacent the free edge of the door; of a latch mounted on the door at its free edge and movable with equal freedom in opposite directions; and a flexible connection between the shaft and said movable latch, whereby, 110 when the shaft is rotated, to close the door, the shaft is movable in one direction and the latch in the opposite direction to bring the latch over the shaft to thereby transfer the load to the latter. 115

2. In a door operating mechanism for a vehicle having a pivoted door and a frame, the combination with a rotatable and bodily movable shaft mounted on the frame adjacent the free edge of the door; of a latch 120 mounted on the door to slide with equal freedom both in a direction toward and from the pivotal axis thereof at the free edge of the door; and a flexible connection 125 between the shaft and sliding latch whereby, when the shaft is rotated to close the door, the latch is slid outwardly of the door and the shaft is moved in the opposite direction to bring the latch over the shaft and thereby transfer the load to the latter. 130

3. In a door operating mechanism for a vehicle having a pivoted door and a frame, the combination with a rotatable and bodily movable shaft supported from the frame adjacent the free edge of the door; of a latch mounted on the door at its free edge and movable with equal freedom in opposite directions; a flexible connection between the shaft and said movable latch, whereby when the shaft is rotated to close the door, the shaft is movable in one direction and the latch in the opposite direction to bring the latch over the shaft to thereby transfer the load to the latter; and cooperable inter-engaging means on the latch and shaft.
4. In a door operating mechanism for a vehicle having a pivoted door and a frame, the combination with a rotatable and bodily movable shaft mounted on the frame adjacent the free edge of the door; of a latch mounted on the door to slide with equal freedom both in a direction toward and from the pivotal axis thereof at the free edge of the door; a flexible connection between the shaft and slidable latch whereby, when the shaft is rotated to close the door, the latch is slid outwardly of the door and the shaft is moved in the opposite direction to bring the latch over the shaft and thereby transfer the load to the latter; and cooperable inter-engaging means on the latch and shaft.
5. In a dump car having a pivoted floor door and cross bearers, the combination with a rotatable and bodily movable operating shaft mounted in said cross bearers adjacent the free edge of the door and extending parallel to the free edge of the door; of a latch movably mounted on the door at its free edge; a flexible connection between said shaft and latch; and a toothed wheel on the shaft in line with said latch, the outer end of the latter being toothed to cooperate with said toothed wheel.
6. In a dump car having a pivoted floor door and cross bearers, the latter being slotted adjacent their outer ends; the combination with an operating shaft rotatably and bodily movably mounted within said slots; of a latch slidably mounted on the door at its free edge, said latch being movable toward the axis of the door during an opening movement and away from the pivotal axis of the door during a closing movement, said latch having a toothed rounded outer end; a toothed wheel secured to the shaft in line with said latch and cooperable with the latter; and a flexible connection between said latch and shaft, the shaft being movable to a position within the free edge of the door when the door is in closed position.
7. In a dump car having a dump door pivotally attached along one edge: the combination with a bodily movable and rotatable shaft disposed adjacent the free edge of the door and extending parallel to the pivotal axis thereof; of a latch slidably mounted on the door at its free edge, the outer end of said latch being arranged to
- of the door when the latter is in closed position and arranged to support the door; of a latch slidably mounted adjacent the free edge of the door in a direction inwardly and outwardly with respect to the pivotal axis of the door, said latch resting upon said shaft when the door is in closed position; means preventing turning of said latch about its longitudinal axis with respect to the door; and a flexible connection interposed between and connected at its ends to said latch and shaft, respectively.
8. In a dump car having a dump door pivotally attached along one edge: the combination with a bodily movable and rotatable shaft disposed adjacent the free edge of the door when the latter is in closed position and arranged to support the door; of devices attached to the shaft and to the door for elevating the latter and moving the shaft to door-supporting position, said devices including, a flexible connection and means automatically adjustable within predetermined limits to vary the effective length of said devices between the points of attachment to the shaft and door and compensate for variable conditions to thereby minimize the strain on the parts in moving the shaft to door-supporting position, said means comprising an element freely movably attached to the door and arranged to rest upon the shaft when the door is in closed position.
9. In a dump car having a dump door pivotally attached along one edge: the combination with a bodily movable and rotatable shaft disposed adjacent the free edge of the door when the latter is in closed position and arranged to support the door; of devices attached to the shaft and to the door for elevating the latter and moving the shaft to door-supporting position, said devices including, a flexible connection and means automatically adjustable within predetermined limits to vary the effective length of said devices between the points of attachment to the shaft and door and compensate for variable conditions to thereby minimize the strain on the doors in moving the shaft to door-supporting position, said means comprising an element freely slidably inwardly toward and outwardly from the pivotal axis of the door and mounted on the latter; and cooperable portions on said shaft and element arranged to register when the shaft is moved to final supporting position.
10. In a door operating mechanism for a vehicle having a pivoted door and a frame, the combination with a rotatable and bodily movable shaft disposed adjacent the free edge of the door and extending parallel to the pivotal axis thereof; of a latch slidably mounted on the door at its free edge, the outer end of said latch being arranged to

rest upon the shaft when the doors are in closed position; means limiting the sliding movement of the latch in both directions with respect to the door; and a flexible connection interposed between and attached at its ends to said latch and shaft, respectively; and cooperable toothed sections on said latch and shaft adapted to 5 register automatically upon relative adjustment between the latch and shaft during a closing movement of the door.

11. In a door operating mechanism for a vehicle having a pivoted door and a frame, 10 the combination with a rotatable and bodily movable shaft disposed adjacent the free edge of the door and extending parallel to the pivotal axis thereof; of a latch slidably mounted on the door at its free edge; means 15 limiting the sliding movement of the latch

in both directions with respect to the door; a flexible connection interposed between and attached at its ends to said latch and shaft, respectively; and cooperable toothed sections on said latch and shaft adapted to 20 register automatically upon relative adjustment between the latch and shaft during a closing movement of the door.

In witness that I claim the foregoing I have hereunto subscribed my name this 15th 25 day of November, 1921.

ARGYLE CAMPBELL.
